CLAIM

The ornamental design for an AC/DC power station, as shown and described.

DESCRIPTION

FIG. 1 is a front, right and bottom perspective view of an AC/DC power station showing my new design;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from circle 9 in FIG. 1; and,

FIG. 10 is a partial enlarged view taken from circle 10 in FIG. 2.

The dash-dash broken lines in the drawings depict the portions of the AC/DC power station which form no part of the claimed design.

The dot-dash broken lines in the drawings depict the boundaries of the partial enlarged views that form no part of the claimed design.
